PUFFED WHEAT AND METHOD OF
MAKING SAMEJohn M. Baer; Chicago, Ill., assignor to Guardite
Corporation, a corporation of DelawareNo Drawing. Application June 12, 1953,
Serial No. 361,411

15 Claims. (Cl. 99—82)

1

This invention relates to a puffed cereal and method of preparing same, and particularly to puffed wheat.

The present application is a continuation-in-part of my copending application, Serial No. 296,963, filed July 2, 1952, now abandoned, which in turn is a continuation-in-part of my applications, Serial No. 40,630, filed July 24, 1948, now abandoned, and copending Serial No. 189,679, filed October 11, 1950, now abandoned. My application, Serial No. 189,679, filed October 11, 1950, was a continuation-in-part of my following applications: Serial No. 34,821, now abandoned; Serial No. 34,822, now abandoned; and Serial No. 34,823, now abandoned, all filed July 23, 1948; Serial No. 23,369, filed April 28, 1948, now abandoned; Serial No. 38,179, filed July 10, 1948, now abandoned; and Serial No. 40,630, filed July 24, 1948, now abandoned.

Reference is had to the related cases of John M. Baer and Frank B. Doyle, Serial No. 62,984, filed December 1, 1948; Allison and Carman, Serial No. 161,744, filed May 12, 1950, now abandoned; Carman and Allison, Serial No. 259,313, filed November 30, 1951, now abandoned; and Carman and Allison, Serial No. 275,458, filed March 7, 1952, now abandoned.

The problem of puffing organic cellular material such as wheat involves a large number of interlocking variables. The wheat cells are such as will trap expanding gas and thus provide the pressure differential necessary for puffing. A sudden drop in pressure must be provided of such amount to produce the pressure difference necessary not only to expand the cell walls but to do so in spite of the leakage that necessarily occurs. On the other hand, the pressure difference must be great enough to exceed the elastic limit of the material before puffing has occurred. The expansibility of the cell wall normally depends upon the moisture content of the product, the condition of that moisture as to being free or combined, the temperature of the article and its chemical condition, particularly as to whether it is cooked or uncooked.

Likewise, there must not only be the pressure difference required to institute puffing, but there must be a volumetric increase of the gases involved sufficient to maintain it.

I have now found that another factor involved, which has hitherto been completely overlooked but the accomplishment of which is inherent in the operation described in my previous applications referred to, is that once the wheat has been puffed, the puffed condition must be

5 maintained even after the pressure difference has been removed. One of the difficulties encountered in many instances of puffing in the prior art was that the wheat could be puffed, but after puffing would collapse because of the weakened condition of the walls following the leakage out of the gas which produced puffing. This was particularly true if, after puffing, the pressure outside of the puffed wheat was increased.

10 I have now found that by suddenly cooling and dehydrating the product so that its final temperature is below 150° F. and preferably well below 100° F.—as for example, from 32° F. or lower up to, say, 100° F., that the cell walls of the product on puffing are cold set so that on standing or on the application of pressure, even of a greatly increased amount, collapse does not occur.

15 These results are obtained automatically by following the procedures already outlined in my previous applications. In these procedures, the following points are important:

20 1. Substantially all of the air should be removed from the product and replaced by an atmosphere of steam prior to puffing.

25 2. The product should be cooked or moistened by steam or otherwise, preferably by the addition of substantially air-free steam at higher pressure and temperature until the condition of the material is proper for puffing and its moisture content is within the desired range. The use of the process permits the introduction of substantially more moisture than was permissible

30 under the old processes.

35 3. It is preferred that the sudden release of pressure be into a maintained vacuum zone which is initially below 8 inches of mercury absolute. The conditions of the resulting explosion should be such as to cause cold setting of the puffed wheat. This means that in actual practice, employing commercially practicable vacuum equipment, the pressure may ride up somewhat during the puffing step. It is preferred to continue evacuation of the vacuum zone during the

40 puffing step so as to cause cold setting of the puffed wheat. The expansion of air-free steam into a vacuum of 4 inches of mercury absolute will automatically reduce the temperature of the product to approximately 125° F. Reduction of the pressure to 2 inches reduces the temperature approximately to 100° F. Reduction to 1 inch reduces it to about 79° F. and reduction to 0.2 inch reduces it to approximately 34° F.

45 Furthermore, by puffing into a maintained

2

vacuum, it is possible to obtain a greater temperature drop in number of degrees between the maximum and minimum than was ordinarily obtainable heretofore. The result of this greater temperature drop was to permit the evaporation of more water from the product by boiling into steam. This boiling not only maintained the pressure difference for puffing, but the removal of the water helped to cold set the cell walls by reducing plasticity and elasticity. The combination of the moisture reduction plus chilling, particularly below 100° F., has produced results not heretofore obtainable.

In a vacuum process, this reduction of temperature is of particular significance, since the lower the vacuum used the greater is the increase in pressure after the completion of the puffing operation when the material is taken back into the atmosphere. If it were not for the cooling and drying effects, many products would not be able to maintain their puffed condition when the pressure is increased, for example from 2 inches absolute to 30 inches absolute—an increase of fifteenfold.

The removal of the air from inside the wheat grains in the first instance has a number of advantages. In the first place, the oxygen of the air has a deleterious effect on the wheat grains, particularly when they are heated. Secondly, the removal of non-condensable gases increases the permeability of the wheat grains to heat and to steam so that heating will occur uniformly and the steam will penetrate equally to all portions of the wheat grains.

Thus, when it comes to introducing steam for increasing the moisture content of the product and for cooking it to the necessary chemical and physical conditions, the fact that air is not present inside the wheat grains produces a rapidity and uniformity of steaming and cooking not otherwise possible. Because of this greater uniformity and speed, it is possible to go to higher temperatures and pressures than would otherwise be possible. Normally, however, it permits the use of lower temperatures and pressures than otherwise required. As an example of this, raw wheat having a weight of 188 grams per unit of volume (one cup) approximately, was subjected to a series of tests. Various portions of the wheat were cooked for fifteen minutes at thirty-five pounds gauge of steam pressure, in each case after removing substantially all of the air from inside the grains.

In the first group of tests, pressure was then increased to 100 pounds with steam held for fifteen seconds and the product then puffed to the full chamber vacuum of approximately 0.2 inch of mercury absolute. The weight of the wheat grains per cup dropped from an average of 188.5 grams (average of five samples) to 18.7 grams (average of five samples).

The following Table I shows the weights before and after puffing of five samples of wheat.

TABLE I

Raw Wheat	Grams	#875	Grams
1	188	1	19
2	188	2	19
3	188.5	3	18.5
4	189	4	18
5	189	5	19

On the other hand, in the second group of tests after the cooking, the steam was replaced by 100 pounds of air pressure which was held

for fifteen seconds and then the material puffed to the same full chamber vacuum. In this, the five original samples had the same average weight as before but the average weight per cup after puffing, instead of being 18.7 grams was 150 grams for the five samples.

On the other hand, wheat cooked in the same manner for the same time and then having the pressure raised to 115 pounds with steam air-free, held for fifteen seconds and then puffed to atmosphere showed an average final weight per cup of 60.1 grams for five samples as compared to the 18.7 when puffed to the vacuum. 115 pounds was used here in order to have the same pressure differences as in the first one in which the 100 pound pressure was puffed to full vacuum.

The Doyle patent, No. 2,627,221 which issued February 3, 1953, shows a puffing apparatus particularly suitable for carrying out the processes herein described. In such an apparatus a steaming chamber is provided within which the product may be placed. This steaming chamber is connected by a triggered door to an expansion chamber. The expansion chamber is preferably kept at a very low pressure, means being provided to maintain a low pressure during the puffing. The steaming chamber is provided with evacuating means, steaming means, and usually with a purge line through which non-condensable gases can be eliminated as well as some condensed steam which is developed during steaming.

As an example of the process, durum wheat was introduced to the steaming chamber. Air and other non-condensable gases were removed from the wheat grains by reducing the pressure in the steaming chamber to about 0.2 inch of mercury absolute while withdrawing the generated steam, the wheat being at a temperature of not less than about 40° F. Saturated steam was then introduced and the pressure increased to 35 pounds gauge, and held at this point for 15 minutes to substantially completely cook the material without loss of cellular identity. The steam pressure was then raised to 100 pounds per square inch gauge, held for 15 seconds, following which the wheat was fired into the expansion chamber which in this instance was at a pressure of 0.2 inch of mercury absolute. This firing is done by suddenly releasing the triggered door of the expansion chamber and the resulting explosion ejects the wheat into the expansion chamber. The potentiometer indicated a temperature at the moment of the puff of slightly below 32° F. indicating an actual super-cooling of the material. This was done by opening the triggered door of the puffing apparatus and firing the wheat into the expansion chamber. The pressure within the expansion chamber was maintained at a low point by continuing the evacuation during the puffing and normally the pressure in that chamber was not permitted to exceed 4 inches of mercury absolute and preferably not permitted to exceed 2 inches of mercury absolute. In some instances, however, I have operated successfully with the pressure in the expansion chamber following the explosion riding up to as high as 4 to 8 inches of mercury absolute as measured on a standrad mercury manometer, but in most instances the pressure was reduced below 4 inches of mercury absolute within a few minutes and before reimposition of atmospheric pressure.

The actual values of the variables in the cook-

ing-puffing cycles of this method depend upon the condition and type of wheat being used, as well as the degree of puffing desired.

The wheat grains in their normal dry state may be employed without moistening. However, in some instances, it may be desired to supply flavor, and/or moistening, and/or nutritional values to the grain, prior to, during, or after puffing. This may be done by the use of a liquid carrier, such as water, under high temperature and pressure which is exploded into the vessel maintaining the product under high vacuum in an atmosphere of steam. By using water under a pressure and temperature corresponding to that, of say, 100 pounds gauge of steam, the particles may be exploded into a fine mist which will penetrate the grains, particularly after they have been puffed. In this way moisture, sugar, salt, certain vitamins, and nutritional salts may be supplied to the material with or without other flavoring agents. This may be done immediately following the initial evacuation (i. e., during cooking) or immediately following the puffing. It is less economical to do it at some intermediate stage.

The wheat should be thoroughly cooked for desirable puffing. I have found that cooking at from about 35 to 100 pounds steam pressure gauge for a period of from about 1½ to 15 minutes produces satisfactory results. Following cooking in the steaming chamber, the steam pressure was adjusted to from about 50 to 100 pounds gauge, after which the pressure was then immediately reduced to sub-atmospheric, preferably below 8 inches of mercury absolute and particularly to about 0.2 inch of mercury absolute.

The resulting vacuum puffed wheat has a volume of from about 4 to 10 times the original grains, as determined by their cup weights. Put conversely, the specific gravity as determined by cup weights is from about 10% to 25% of the specific gravity of the original wheat grains. The vacuum puffed wheat particles are everted, substantially pure white except for the bran particles adhering thereto, and are entirely different in shape from the original wheat grains. The cellular structure is vitreous in appearance. On cross-section, the puffed grains have a large number of relatively large cavities substantially uniformly distributed throughout the interior. These cavities while by no means spherical are generally rounded at their protuberances.

The vacuum puffed wheat grains are immediately wettable by water, except in those portions protected by the bran fragments and when immersed in water at 65° F., for a period of 10 minutes, they retain their entity and shape and do not break down even when mashed on a microscopic slide.

Examples of applying the method of this invention are:

Example 1

Red durum wheat was placed in a steam chamber which was then evacuated to an absolute pressure of about 0.2 inch of mercury absolute, the temperature of the wheat being not less than about 40° F., to remove substantially all of the non-condensable gases. The wheat was then steamed to a pressure of 35 pounds per square inch gauge, held there for 8 minutes accompanied by continual purging of the steam, quickly steamed to 100 pounds gauge, held there for about 15 seconds, and then fired into the expansion chamber which was at a pressure of 0.2 inch of mercury absolute. Evacuation of the expansion

chamber was continued during the puff until the grains were cold set.

Example 2

Red durum wheat (15 pounds) was placed in the steam chamber and the pressure reduced to about 0.2 inch of mercury absolute for 2 minutes, the wheat being at a temperature of not less than 40° F., to remove substantially all of the non-condensable gases. The wheat was then steamed to a pressure of 100 pounds per square inch gauge, held there for 2 minutes accompanied by continual purging of the steam, and then fired into the expansion chamber which was at a pressure of 0.2 inch of mercury absolute. Evacuation of the expansion chamber was continued during the puff until the grains were cold set.

Example 3

Red durum wheat (5 pounds) was placed in the steam chamber and the pressure reduced to 0.2 inch of mercury absolute for 2 minutes, the wheat being at a temperature not less than about 40° F., to remove substantially all of the non-condensable gases. The wheat was then steamed to 75 pounds per square inch gauge in ½ minute, held there for 1½ minutes accompanied by continual purging of the steam, and then fired into the expansion chamber which was at a pressure of 0.2 inch of mercury absolute. Evacuation of the expansion chamber was continued during the puff until the grains were cold set.

Example 4

Wheat (5 pounds) was placed in the steam chamber and the pressure reduced to 0.2 inch of mercury absolute for 2 minutes, the wheat being at a temperature not less than 40° F., to remove substantially all of the non-condensable gases. The wheat was then steamed to a pressure of 75 pounds per square inch gauge, held there for 4 minutes accompanied by continual purging of the steam, and then fired into the expansion chamber which was at a pressure of 0.2 inch of mercury absolute. Evacuation of the expansion chamber was continued until the grains were cold set.

Example 5

Red durum wheat (20 pounds) was placed in the steam chamber and the pressure reduced to about 0.2 inch of mercury absolute for 2 minutes, the wheat being at a temperature not less than about 40° F., to remove substantially all of the non-condensable gases. The wheat was then steamed to a pressure of 100 pounds per square inch gauge, held there for 5 minutes, following which the steam pressure was quickly reduced to 50 pounds per square inch gauge, and then the wheat was fired into the expansion chamber which was at a pressure of 0.2 inch of mercury absolute. Evacuation of the expansion chamber was continued during the puff until the grains were cold set.

Example 6

Wheat was treated in the same manner as in Example 1 except that in the step of removing the non-condensable gases from the wheat grains prior to steaming, the period of evacuation at 0.2 inch of mercury absolute pressure was 1 minute instead of 2 minutes.

Example 7

Wheat was treated in the same manner as in Example 1 except that in the step of removing the non-condensable gases from the wheat grains

prior to steaming, the period of evacuation at 0.2 inch of mercury absolute pressure was 5 minutes instead of 2 minutes.

Example 8

Wheat (20 pounds) was placed in the steam chamber and the pressure reduced to 0.2 inch of mercury absolute for 2 minutes, the wheat being at a temperature not less than about 40° F., to remove substantially all of the non-condensable gases from the wheat grains. The wheat was then steamed at a pressure of 100 pounds per square inch gauge in 95 seconds, held there for 5 minutes and then fired into the expansion chamber which was at a pressure of 0.2 inch of mercury absolute. The pressure in the expansion chamber was kept below 4 inches of mercury absolute during the puff until the grains were cold set.

The puffed wheat grains from Examples 1 to 8 were very satisfactory, having the above described characteristics. Samples of the vacuum puffed wheat from the examples showed from 11% to 15% thiamine retention and 78% to 87% lysine retention. A standard commercial puffed wheat showed 0 thiamine retention and 35% lysine retention. The sample from Example 6 had the 11% thiamine retention determination and that from Example 7 had the 15% thiamine retention determination.

The lysine retention was likewise greater for the vacuum puffed wheat product which had been evacuated for 5 minutes before steaming, i. e., Example 7.

The puffed wheat product produced by the process of this method showed 51% nitrogen efficiency by a feed test compared to a negative efficiency for a corresponding commercially puffed wheat.

The foregoing detailed description has been given for clearness of understanding only, and no unnecessary limitations should be understood therefrom for some modifications will be obvious to those skilled in the art.

I claim:

1. The method of puffing wheat which comprises: freeing wheat grains from air and replacing the air with an atmosphere of steam, cooking the wheat grains for a period sufficient to soften the cell walls and adapt them for puffing, then subjecting the wheat grains to a sudden change from a high super-atmospheric pressure to a low sub-atmospheric pressure whereby they are puffed.

2. The method as set forth in claim 1 in which the wheat grains are cooked under a pressure of steam of approximately 35 to 100 pounds per square inch gauge.

3. The method as set forth in claim 1 in which the wheat grains are cooked under a pressure of steam of approximately 35 to 100 pounds per square inch gauge, the pressure adjusted to from 50 to 100 pounds per square inch gauge, and then instantaneously reducing the pressure by shooting the wheat grains into a low sub-atmospheric pressure whereby they are puffed.

4. The method as set forth in claim 1 in which the wheat is cooked for a period of from 1½ to 15 minutes at a pressure of from 35 to 100 pounds per square inch gauge.

5. The method which comprises cooking wheat in an atmosphere of steam, suddenly re-

ducing the pressure below 8 inches of mercury absolute to puff the wheat and then drying the puffed wheat under the sub-atmospheric pressure.

5 6. The method as set forth in claim 5 in which the drying is accomplished while supplying heat to the wheat.

10 7. The method which comprises puffing wheat by a sudden reduction in pressure in an atmosphere of steam and concluding the operation at an absolute pressure substantially below 8 inches of mercury absolute, and then introducing a volatile liquid at a temperature sufficiently high to have an internal vapor pressure markedly above atmospheric, said mist containing additive flavoring or nutritive ingredients, whereby the liquid explodes into a fine mist and penetrates the wheat.

15 8. In the puffing of wheat, the steps of heating the wheat in the presence of moisture to produce a super-atmospheric steam pressure thereon and then puffing the product into a maintained vacuum sufficiently low to cold set the product by evaporation of moisture from and consequent cooling of the product and reimposing atmospheric pressure upon the product while in cold set condition.

20 9. The process of claim 8 in which the puffing operation is carried out as a batch process, the puffing being into a vacuum which is initially at substantially absolute zero pressure and which rises during the puffing operation to a point not above an average pressure of 4 inches of mercury absolute.

25 10. The process of claim 8 in which the puffing operation is carried out as a batch process, the puffing being into a vacuum which is initially at substantially absolute zero pressure and which rises during the puffing operation to a point not above an average pressure of 2 inches of mercury absolute.

30 11. The method of claim 8 in which the product is dried after the puffing operation is complete but before reimposition of atmospheric pressure.

35 12. The method of claim 8 in which the temperature of the product is reduced below 100° F. before reimposition of atmospheric pressure.

40 13. The method of claim 8 in which the temperature of the product is reduced below 50° F. before reimposition of atmospheric pressure.

45 14. The method of claim 8 in which the temperature of the product is reduced below 150° F. before reimposition of atmospheric pressure.

50 15. A cold set, vacuum puffed wheat product produced by the process set forth in claim 8.
